FOOD PACKAGE CUP OR SIMILAR ARTICLE

Donald W. Donovan, Glastonbury, Conn., assignor to Monsanto Company, St. Louis, Mo.

Filed Nov. 17, 1969, Ser. No. 20,134

Term of patent 14 years

Int. Cl. D9—04

U.S. Cl. D9—220

FIG. 1

FIG. 3

FIG. 1 is a perspective view of a food package cup or similar article showing my new design;

FIG. 2 is a side elevational view thereof; and

FIG. 3 is a partial sectional view taken through line 3—3 of FIG. 2.

I claim:

The ornamental design for a food package cup or similar article, substantially as shown.
